DISPLAY CABINET

Robert B. Welch, Portland, Oreg., assignor to Revolva Products, Inc., Portland, Oreg., a corporation of Oregon

Application December 6, 1954, Serial No. 33,396

Term of patent 14 years

(Cl. D80—9)

FIG. 1

FIG. 3

The dotted line portions of the drawing are for purposes of illustration only.

1 claim:

The ornamental design for a display cabinet, as shown and described.
